UNITED STATES PATENT OFFICE.

ALBERT V. PICKERING, OF WEST TOWNSEND, MASSACHUSETTS, ASSIGNOR TO TOWNSEND MANUFACTURING CORPORATION, OF WEST TOWNSEND, MASSACHUSETTS, A CORPORATION OF MASSACHUSETTS.

OIL BURNER.

Application filed August 4, 1923. Serial No. 655,690.

To all whom it may concern:

Be it known that I, ALBERT V. PICKERING, a citizen of the United States, residing at West Townsend, in the county of Middlesex and State of Massachusetts, have invented certain new and useful Improvements in Oil Burners, of which the following is a specification.

This invention relates to oil burners and 10 more particularly to oil burners of the type suitable for installation in the heating systems of residences, eliminating the necessity of reliance on coal for heating, but the invention is not limited to this special use 15 since it may readily be put to other uses and employed in varied environments as those skilled in the art will recognize from the following description of its novel features.

20 Heretofore difficulty has been experienced in obtaining a perfect combustion, in oil burners of the kind in question, the soot and smoke making such burners unfit for installation in residences, apartments, hotels and the like. Another feature of the usual commercial oil burner, that is a deterrent to its use by the householder, is its 25 noisiness. Other features that are disadvantageous are the necessity of constant 30 clearing due to imperfect combustion, the cost of upkeep, and the initial expense of installation.

The object of the present invention is to provide an oil burner which is simple in construction, can be installed and maintained at low cost in any of the present coal burning house heating systems, and is so designed that perfect combustion is obtained, without noise, and with a maximum 40 of heat from the burning oil.

The preferred form of the invention is illustrated in the accompanying drawings in which:

45 Figure 1 is a view of a typical house heater, in elevation, with the side wall broken away to show the location of my oil burner within it, this view including also an indication of the control system which will form the subject matter of a separate 50 application for Letters Patent of the United States;

Fig. 2 is a view, in plan, of the oil burner, omitting the supply and overflow pipe lines shown in Fig. 1; and

Fig. 3 is a view, in vertical cross-section, 55 of the burner shown in Fig. 2 taken on the line 3—3 thereof.

In the embodiment of the invention illustrated in the drawings the main features of the complete apparatus comprise a burner 60 4 supported at the proper height within the heater; an air intake pipe 6 which conveniently may extend from the fire pot door; oil supply and discharge pipes 8 which may enter through the ash pit door; 65 a control box or casing 10 outside the heater within which are the automatic shut off mechanism and the control valve, the stems of the latter being operated from outside the box; a blower 11 for forced draft, if 70 such is requisite; and an oil storage and supply system of any convenient type (not shown in the drawing).

The burner 4, which forms the important feature of the present invention, comprises 75 a bowl-like lower member 12 having a central cone-like structure 14, the peripheral wall of which is provided with a series of circular walls 16 forming oil receiving troughs 18 which decrease in diameter from 80 bottom to top of the cone. The circular outer wall 20 of the uppermost trough encloses a flat surface at the top of the cone forming a cup. The cone is bored through centrally at 22 and this bore receives, in 85 its upper end, a burner-tip 24, of novel construction to be described later, which rests in the cup and co-operates with the wall 20 to form an upper oil receiving trough or reservoir 26.

90 Resting on the upper, circular edge of the burner bowl 12 is a heat-block 28, of considerable mass, the mode of support comprising three radial legs 30 having shoulders for engaging the edge of the 95 bowl, thus holding the heat-block in central position thereon. The block 28 is provided with a central opening 32 which flares outwardly at its lower portion through which air for combustion is introduced and 100 discharged down upon the cone 14 and upon the oil reservoir 26. The heat-block also

2
serves as a deflector and is so designed as to co-operate with the burner-bowl, as will presently appear, to produce a blast from the burning oil. The air intake pipe 6 is in the form of an L leading downward to the bore 22 from the fire pot door of the heater in which the oil burner is installed.

The bottom of the burner bowl is provided with a plurality of vertical bosses 34, 10 three being shown in the drawings, which receive the upper end of extensible legs 36 of any suitable construction. The lower ends of the legs fit into a supporting frame 38 which rests on the ash pit floor of the 15 heater. By adjusting the legs, the burner may be supported at the required height to properly join with the inner end of the air intake pipe 6 when this pipe is fitted to the fire pot door opening.

20 Leading into the lower end of the oil feed bore 22 is an oil supply pipe 40 which may be fitted with a flare-back fire screen 41 of any suitable form. The pipe 40 leads forwardly, through the ash pit door, from the 25 control box 10 and to the control box leads from the oil supply tank, as usual. The burner-bowl 12 is provided, at its forward side, with an oil overflow outlet 42 from which leads a discharge pipe 44 to a drip 30 pan within the control box which functions to shut off the oil supply in a novel manner and will be claimed in said companion application.

If a blower 11 is employed it, with its 35 motor, may be mounted on a stand 46 and its air conduit 47 having a discharge nozzle 48 opposite the intake pipe 6, may be supported from the control box, as by the support 49. In locations where the natural 40 draft is sufficient, the forced draft may, of course, be dispensed with.

The form and proportions of the burner-bowl 12 and heat-block or deflector 28 are of extreme importance in obtaining perfect 45 combustion. The construction of the burner-tip 24 which supplies the oil to the adjacent oil reservoir 26 is also of importance. These features will now be described.

It will be observed that the inner 50 caved surface 50 of the burner-bowl 12 flares outwardly and upwardly from the base of the central cone structure 14 and that its edge lies fairly close to the peripheral surface of the deflector 28, which is 55 nested therein. Also the lower convex surface 52 of the deflector flares outwardly and upwardly which, at its peripheral face, is substantially the complement of the cavity presented by the burner-bowl chamber. These two surfaces act to direct and 60 lead the products of combustion to, and through, the annular opening between the two members, by virtue of which the heat is delivered in a strong blast both outwardly 65 and upwardly as is desired for household

heater installations. In designing these two parts of the burner care should be taken that the flame outlet area between the two parts is not greater than the area of the air inlet formed by the pipe 6. In practice 70 these areas are made equal since, with this construction, a substantially constant velocity of the hot gases flowing outward is maintained. As a result, the burning gases 75 form a white blast, completely consuming the fuel without soot or smoke and eliminating carbonization.

The burner-tip 24 comprises a removable part slipped into a counter bore, of the character shown in Fig. 3 at the upper end 80 of the oil supply bore 22. The tip has a cylindrical head 54 rising centrally from a base 56 of larger diameter, the upper surface of which forms the bottom of the oil 85 reservoir enclosed by the annular wall 20. The head is provided with two oppositely disposed, horizontal slots 58 near its base which extend inward and communicate with the upper end of a vertical oil supply bore 60 extending through the base 56. With this construction the oil, under pressure, 90 constantly flows out of the side ports 58 to maintain a supply in the trough 26, the head 54 preventing the air blast from above from interfering with this operation. The air 95 entering the heat chamber travels against and is heated by the block 28 and the downward blast of hot air sprays the oil outward over the wall 20 into the heat chamber where its gases are completely consumed. 100 The area of the oil inlet port is such that the proper mixture of oil and air for combustion, is obtained.

In operating the burner, the bowl 12 is 105 first filled through a pilot line, while cool, until the several troughs and the lower part of the burner bowl are filled, the latter to the level of the discharge outlet 42. This oil is lighted by forcing lighted paper down the air intake pipe 6 and ordinarily is sufficient to warm up the parts of the burner. Additional oil may be supplied through the 110 pilot line until sufficient oil has been burned to thoroughly heat the walls of the heat chamber and the heat-block 28. The full 115 supply of oil through the main line may now be fed to the burner-tip and the draft through the intake pipe 6 started. It will be observed that, after lighting, the air in the intake pipe is pre-heated thus materially aiding the perfect combustion that is obtained. The heat-block 28 heats to a cherry red and the oil sprayed by the hot air blast over the hot wall 20 and under the hot surface 52 of the deflector instantly volatilizes and is blown outward in a white blast, the 120 described form of the enclosing surfaces permitting the blast to sweep freely outward through the annular outlet between the bowl and deflector. The fuel used by pref- 125 130

rence is commercial furnace oil but other fuels may readily be used and my invention is not limited to the use of furnace oil.

The drawing, in Fig. 1, indicates a thermostatic or other control of the oil supply through connection to a throttle valve in the main oil supply line and those skilled in the art will recognize that my novel burner may be employed with any other usual features of control with which these systems are supplied.

Having thus indicated the scope of my invention and having specifically described its preferred form, what is claimed as new, 15 is:—

1. A burner of the class described having, in combination, a lower member having a concaved inner surface, an upper member having a convexed lower surface nested 20 within said lower member in a manner to form a heat chamber therebetween and having a form near the circumference substantially the complement of said concaved inner surface to form a curved conduit gradually narrowing toward the outlet and provide a narrow slit, means for conducting oil to the heat chamber through the lower member, and means for conducting air to the heat chamber through the upper member.
2. A burner of the class described having, in combination, a lower member of bowl-like form having a central conical projection provided with a vertical oil inlet leading to the top thereof, an upper member

having a convexed lower surface, supported 35 on the upper edge of said lower member in spaced relation thereto to form a flame outlet slit between them, having an air intake above said oil inlet, and a burner tip in said inlet closing it against an inrush of 40 air provided with side ports for supplying oil for consumption in the heat chamber between said members.

3. A burner of the class described, comprising a lower member having a central 45 cone-like construction with a cup-like cavity at the top and having an oil supply bore up through it into said cavity, and a cap having a base detachably mounted and fitting in said cavity and provided with a central passage communicating with said bore and opening outwardly in opposite directions below the top of said cap and the top of said cavity, which cavity constitutes an oil reservoir.

4. A burner of the class described having, in combination, a lower member provided with a central oil inlet port, a cap in said inlet port constructed to deliver the oil sidewise therefrom, an open oil reservoir surrounding the cap and within which the cap is located so as to deliver the oil into the reservoir, and an upper member of considerable mass, supported within but in spaced relation to said lower member, having an air intake arranged to deliver air directly upon the oil in said reservoir.

ALBERT V. PICKERING.
